[57] CLAIM

The ornamental design for a sports helmet, as shown.

DESCRIPTION

FIG. 1 is a top, front right-side perspective view of a sports helmet showing our new design;
FIG. 2 is a front perspective view thereof;
FIG. 3 is a rear perspective view thereof;
FIG. 4 is a left side perspective view thereof; and,
FIG. 5 is a bottom, right-side rear perspective view thereof.
The sports helmet of the invention is used to protect the head of the sportsman or sports woman in a number of a wide variety of sports including hockey, biking, skiing, motor racing, horseback sports, wrestling, boxing, racing, walking and racket sports.
